No. 887,350.

PATENTED MAY 12, 1908.

E. H. SLICK.
BEVELING MACHINE.
APPLICATION FILED SEPT. 24, 1906.

UNITED STATES PATENT OFFICE.

EDWARD H. SLICK, OF SOUTH BEND, INDIANA.

BEVELING-MACHINE.

No. 887,350.

Specification of Letters Patent.

Patented May 12, 1908.

Application filed September 24, 1906. Serial No. 335,916.

To all whom it may concern:

Be it known that I, EDWARD H. SLICK, a citizen of the United States, residing at South Bend, in the county of St. Joseph and 5 State of Indiana, have invented certain new and useful Improvements in Beveling Machines, of which the following is a specification.

This invention relates to card beveling machines.

One object is to provide a machine embodying characteristics in its organization of elements that simplicity, inexpensiveness, durability and accuracy in operation will be 15 essential features.

Another object resides in the provision of a card beveling machine constructed and arranged whereby the card may be firmly clamped upon a reciprocating carriage 20 operating with a fixed cutting member.

With the above and other objects in view, the present invention consists in the combination and arrangement of parts, herein-after more fully described, illustrated in the 25 accompanying drawings, and particularly pointed out in the appended claims, it being understood that changes may be made in the form, proportion, size and minor details without departing from the spirit or scope of 30 the invention and without sacrificing any of the advantages thereof.

In the drawings:—Figure 1 is a side elevation of the invention. Fig. 2 is a top plan view, and Fig. 3 is a transverse sectional 35 view of the carriage, illustrating in elevation the clamping bar and the means for operating the latter.

Referring now more particularly to the accompanying drawings, the reference char- 40 acter 1 indicates a suitable table upon which is secured fixedly, in any suitable manner, an angular arm 2, whose extremity is enlarged to form a head 3.

A segmental shaped bevel adjusting head 45 4 is pivoted at its minor end to the head 3 of the arm 2, by means of a suitable pivot 5, and near the major end of the segmental head 4 there is provided a curved slot 6 for working fit upon the bolt 7. By loosening the nut 8 50 of the bolt 7 the beveling head 4 may be adjusted to different inclinations upon its pivot 5 and tightened against movement by operating the said nut 8. The outer edge of the adjusting head 4 is provided with a substan- 55 tially elongated clamping lug 9 arranged

preferably upon an inclination, for coöperating with a comparatively short clamping lug 10 formed upon the corresponding face of the head 4. These clamping members 9 and 10 are designed to hold between them, 60 in an inclined plane the beveling tool element holder 11, there being an operating screw 12 supported in the eye 13 of the head 4 and piercing the clamping lug 10 for engagement with the holder 11. By this means the holder 65 11 may be held firmly in position to support the beveling blade or other suitable element 14 in proper position to bevel the cards in the manner hereinafter more fully described. As shown in dotted lines in Fig. 70 1, one face of the holder 11 is provided with a longitudinal groove 15 for the reception of the cutting element 14, and the cutting element 14 is held against longitudinal movement with respect to the holder 11 by means 75 of a suitable clamping element 16 arranged preferably at the upper end of the holder and beveling element, as clearly shown in Fig. 1.

In order that the beveling tool and its holder may be adjusted to different inclinations, it is only necessary to move the adjusting head 4 in the manner hereinbefore described, and to effect an adjustment of the holder and beveling element longitudinally of the clamping member 9, the holder 11 is 80 provided with a curved arm 17 directed toward the head 3 and provided in its extremity with a screw threaded eye for reception of the screw threaded bolt 18, whose lower end is adapted to rest upon the upper face of 90 the head 4. It will thus be understood that by loosening the operating bolt 12 and turning the screw 18, the holder 11 and its tool may be adjusted accordingly.

From the foregoing it will be understood 95 that in operation, the beveling element 14 is held in a fixed position, and, as hereinbefore stated, this element is designed to coöperate with movable means carrying the card. This movable means consists of a carriage 19 100 provided with depending parts 20 and 21 designed to engage the upper faces of the tracks 22 and 23, respectively, of the table 1. These track ways 22 and 23 are preferably greased and the first named track 22 is pref- 105 erably beveled at its upper end, as indicated at 24, for engagement in the correspondingly formed groove 25 of the depending part 20 to prevent disengagement of the carriage 19 with respect to the tracks.

To hold the card upon the carriage 19, there is provided a slot 26 in the carriage near the outer end thereof for coöperation with the clamping bolt 27 of the head block 28 de-
 5 signed to slide upon the carriage for engagement with the outer ends of the cards (not shown) according to the size of the latter. At the inner end of the carriage 19 is pro-
 10 vided a bar 29 whose opposite ends may or may not be reduced, as shown at 30 in Fig. 3, but which are in any event pierced by suitable eye bolts 31 extending through the de-
 15 pending parts 20 with their eyes therebe-
 20 neath for the rotatable reception of the cam shaft 32 provided near each end with a cam 33 for engagement with the under faces of the de-
 25 pending parts 20 upon proper operation of the end lever 34. This clamping bar 29 is normally out of contact with the upper face
 30 of the carriage 19 and this normal spacing of the clamping bar, with respect to the carriage, is accomplished through the instru-
 35 mentality of suitable helical or other springs encircling the corresponding eye bolts 31
 40 and seated in the recess 36 formed through the carriage and each of the depending parts 20. It will thus be understood that the head block 28 is adjusted according to the size of the card whose edge is to be beveled
 45 and that the clamping bar 29, through the operation of the cam shaft 32 is brought down tightly upon the inner edge of the card to hold it firmly against slipping movement upon the carriage. The carriage 19 is then
 50 moved across the table 1 upon the tracks 22 and 23. The inner end of the card, traveling in the path of the fixed beveling tool 14, is beveled according to the desire of the operator. The carriage may be moved manually
 55 or otherwise backward and forward over the track ways in the path of the beveling element to present the card properly to the latter to effect the desired result.

What is claimed is:—

- 45 1. In a device of the class described, a supporting frame having spaced guide tracks, a table movable upon said tracks, an arm carried by said frame, a head member swinging upon said arm and provided with a
 50 clamping rib, means for adjusting said head member relative to said arm, a holding element having a longitudinal channel in one face and bearing with its channeled face against said rib, a tool adjustably disposed
 55 in said channel and bearing against said rib, means carried by said table for supporting a card, means for adjustably clamping said tool in said holder, means for adjusting said holder in engagement with said rib, and
 60 means for adjusting said holder and the tool carried thereby longitudinally of the rib to

dispose the cutting edge of the tool in the path of said card.

2. In a device of the class described, an arm, a movable table, card supporting means carried by said table, a head member swinging from said arm and provided with a clamping rib, means for adjusting said head member relative to said arm, a holding element having a longitudinal channel in one face and bearing with its channeled face against said rib, a tool adjustable in said channel and bearing against said rib, means for adjustably clamping said tool in said holder, means for adjusting said holder in engagement with said rib, and means for adjusting said holder and the tool carried thereby longitudinally of the rib to dispose the cutting edge of the tool in the path of said card. 80

3. In a device of the class described, an arm, a movable table, card supporting means carried by said table, a head member swinging from said arm and provided with a clamping rib, means for adjusting said head member relative to said arm, a holding element having a longitudinal channel in one face and bearing with its channeled face against said rib, and provided with a projecting arm having a threaded transverse aperture, an adjusting screw engaging the threaded aperture of said holder arm and bearing against said swinging head member, a tool movable in the channel of said holder and bearing against said clamping rib, means for adjustably clamping said tool and said holder, and means for adjusting said holder in engagement with the said rib. 95

4. A card beveling machine comprising a table, a carriage slidably mounted upon the table, an arm fixed upon the table, a tool carrying member pivotally mounted upon the arm provided with spaced clamping elements, a tool holder mounted between said spaced elements, means coöperating with the spaced elements to hold the tool holder member against movement, the tool holding member having a curved lug, means piercing the free end of the lug for engagement with the upper face of one portion of said arm to 100 adjust the tool holding member toward and away from the carriage, a beveling tool carried by said holder, and means for clamping the tool to the holder. 110

In testimony whereof I have signed my 115 name to this specification in the presence of two subscribing witnesses.

EDWARD H. SLICK.
